LOADING, FIRING AND UNLOADING MECHANISM FOR A FIREARM WITH A LATERALLY ACTUATED BREECH CLOSURE

Richard H. Colby, South Hadley, Mass., assignor to the United States of America as represented by the Secretary of the Army

Filed Oct. 7, 1959, Ser. No. 845,043

7 Claims. (Cl. 89—169)

(Granted under Title 35, U.S. Code (1952), sec. 266)

The invention described herein may be manufactured and used by or for the Government for governmental purposes without the payment of any royalty thereon.

This invention relates to automatic firearms which are recoil operated and more particularly to the breech mechanisms thereof. This application is a continuation-in-part of a previous application, Serial No. 429,706, filed May 13, 1954 and entitled "Operating Mechanism for a Short Firearm."

It is an object of this invention to provide for such firearms a breech mechanism which is compactly designed so as to require a small-sized receiver suitable for mounting in a limited space, as in a tank.

It is another object of this invention to provide for such firearms, which have a laterally actuated breech closure member, a loading and unloading mechanism which is connected to the combined mass of the barrel and barrel extension during functional operation of the mechanism thereby permitting a reduction in the mass of the loading and unloading mechanism so as to require a minimum of space in the receiver.

It is a further object of this invention to provide a carrier for the ramming of cartridges into the firearm barrel and the extraction of the fired cases therefrom with such functions being performed by a rammer and an extractor which are vertically spaced and which extend forwardly from the carrier so as to form a clearance for the passage of the breech closure member when the rammer and extractor are in joint contact with the rim of the chambered cartridge.

It is still another object of this invention to provide a double cam device for actuating the carrier responsive to the reciprocation of the barrel and thereby increase the angular relationship between an accelerator which actuates the carrier and the cam path means for smoothness of operation.

The specific nature of the invention as well as other objects and advantages thereof will clearly appear from a description of a preferred embodiment as shown in the accompanying drawings in which:

Fig. 1 is a side view of the firearm partially cross-sectioned to show the arrangement of the parts when the firearm is in battery;

Fig. 2 is a view similar to Fig. 1 but showing the relationship of the parts when the firearm is in recoil position;

Fig. 3 is a fragmentary view similar to Fig. 1 but showing a cartridge engaged by the front end of the rammer during forward movement of the carrier;

Fig. 4 is a view taken along line 4—4 of Fig. 2;

Fig. 5 is a view taken along line 5—5 of Fig. 1;

Fig. 6 is a view taken along line 6—6 of Fig. 2;

Fig. 7 is a view taken along line 7—7 of Fig. 1;

Fig. 8 is a view taken along line 8—8 of Fig. 7;

Fig. 9 is a view taken along line 9—9 of Fig. 1;

Fig. 10 is a fragmentary side view of the cam arrangement for actuating the accelerator; and

Fig. 11 is a view taken along line 11—11 of Fig. 1.

2

Shown in the figures is a firearm 12 including a rectangular receiver 14 and a feeding mechanism 16 having a laterally disposed tray 18 which is mounted on the top of the receiver. Feeding mechanism 16 is of conventional type and is adapted to successively index linked cartridges 20 at a throat 22 communicating with the inside of receiver 14. A barrel 24 is slidably mounted in the front end of receiver 14 for reciprocation in recoil and counterrecoil strokes responsive to forces produced by the discharge of a cartridge 20 in a chamber 26 of the barrel. A barrel extension 28 is connected to barrel 24 for reciprocation therewith by coupling means, such as shown at 30, and is bifurcated by a vertically disposed channel 32 which provides communication between chamber 26 and an ejection port 34 in the bottom of receiver 14. Channel 32 also forms a pair of vertically disposed side plates 36 which have sliding engagement with the corresponding sides of receiver 14. A pair of springs 38 are disposed between barrel extension 28 and the rear end of receiver 14 for biasing barrel 24 and the attached barrel extension forwardly in a counterrecoil stroke after being compressed during the recoil stroke thereof. Cartridges 20 are successively transferred from throat 22 into chamber 26 by a carrier 40 which is mounted between side plates 36 for longitudinal reciprocation in channel 32 between a forward and a rearward position in axial alignment with barrel 24. Engagement is made between carrier 40 and the cartridge 20 which is indexed in throat 22 by a rammer 42 which extends integrally forward from the top of the carrier. Rammer 42 is provided with a front end 44 which is disposed for contact with the base of the throat indexed cartridge during movement of the carrier to the forward position. A guide portion 46 is disposed at the front end of throat 22 to engageably direct cartridge 20 downwardly into chamber 26 while being moved forwardly by rammer 42. As cartridge 20 assumes a longitudinal position in chamber 26, front end 44 slides over a rim 47 of the cartridge for frictional contact of the rim with an underside 48 of rammer 42 when the cartridge is fully chambered. An extractor 50 is journaled to the underside of carrier 40 by means of a laterally disposed pin 54 for pivotal movement in the same vertical plane occupied by rammer 42. Extractor 50 extends forwardly substantially parallel to rammer 42 so as to jointly contact cartridge case rim 47 therewith and to form a clearance 56 having a purpose to be described hereinafter. A hook 58 is provided at the front end of extractor 50 for releasable engagement with an extractor groove 62 in cartridge 20 so as to remove fired case 64 therefrom during movement of carrier 40 to the rearward position thereof. A spring 66 is disposed between extractor 50 and carrier 40 rearwardly of pin 54 for biasing hook 58 inwardly. The displacement of fired case 64 by the bias of spring 66 is opposed by the contact of rim 47 with underside 48 of rammer 42 and such engagement between the rammer and extractor maintains the fired case longitudinally disposed while being carried rearwardly from chamber 26 by carrier 40. A ramp 60 is formed on the front end of hook 58 for cammingly moving the hook over rim 47 for engagement with extractor groove 62 during forward movement of carrier 40 after cartridge 20 is stripped by contact thereof with the walls of chamber 26. Carrier 40 is actuated between the forward and rearward positions thereof responsive to reciprocation of barrel 24 by means of an accelerator 68 which is pivotally disposed in channel 32 on a pin 70 mounted laterally beyond portion 74 adjacent the right one of the side plates 36 adjacent the bottoms thereof and spaced equidistantly between the location of the rear end of the carrier when in the forward and rearward positions. Accelerator 68

includes a beam 72 which extends upwardly from a hub portion 74 adjacent the right one of the side plates 36 so as to be spaced from the left one thereof sufficiently to leave unobstructed a pathway for the passage of fired case 64 to ejection port 34 as hereinafter described. A roller 76 is rotatably mounted to the left side of the free end of beam 72 for sliding engagement with a vertical groove 78 in the rear portion of the right side of carrier 40 for converting pivotal movement of accelerator 68 to translational movement of carrier 40 and to connect the carrier to the accelerator without free movement therebetween.

The forward and rearward positions of carrier 40 are spaced sufficiently for a cartridge to be transferred thereby from throat 22 into chamber 26 and fired case 64 extracted therefrom during the reciprocation of the carrier. However, the rearward position need not be spaced for an overtravel of carrier 40 so as to gain momentum before rammer 42 contacts the indexed cartridge, as in conventional firearms, because as herein-after described, the masses of barrel 24 and barrel extension 28 are connected to the carrier during the ramming and extraction operation thereof. Also, with the combined mass of barrel 24 and barrel extension being connected to carrier 40, the mass thereof may be reduced so as to occupy little space in receiver 14.

Accelerator 68 is actuated to move carrier 40 between the forward and rearward positions thereof during the rearward half of the reciprocal travel of barrel 24 and barrel extension 28 by means of a double cam device including a rammer arm 80 and an extractor arm 82 which extend integrally from hub portion 74 for cooperation with cam paths 84 and 86 in receiver 14 as described hereinabove. Such double cam arrangement provides a much smoother actuation of accelerator 68 because, in order to move carrier 40 between the forward and rearward positions thereof, beam 72 swings through an angle of 75° which would approach a dead center contact between the engaging portions of the accelerator and a cam if only one thereof was used.

In order to save space in receiver 14 so that accelerator 68 may be journaled to barrel extension 28 adjacent the bottom thereof, rammer arm 80 and extractor arm 82 extend upwardly from hub portion 74. With beam 72 vertically disposed, rammer arm 80 extends upwardly and rearwardly from hub portion 74 in back of the beam and at an angle relative thereto which is equal to one-half that through which the beam must swing to actuate carrier 40, and extractor arm 82 extends upwardly and forwardly from the hub portion on the opposite side of the beam at a similar angle relative thereto.

Cam path 84 is formed in a vertically disposed cam plate 88 which is fixed to the right side of receiver 14 and is engaged by a follower 90 rotatably mounted to the free end of rammer arm 80. Cam path 84 extends arcuately upward and forward in a cam plate 88 and is formed so as to pivot beam 72 between the rearward position thereof and a vertical position responsive to reciprocation of barrel extension 28 and without free movement between follower 90 and the cam path. Cam path 86 is formed in a vertically disposed cam plate 92 fixed to the left side of receiver 14 and is engaged by a follower 94 rotatably mounted to the free end of extractor arm 82. Cam path 86 extends upwardly and rearwardly in cam plate 92 and is formed so as to pivot beam 72 between the vertical and forward positions responsive to reciprocation of barrel extension 28 and without free movement between follower 94 and the cam path while engaged. As best shown in Fig. 10, cam paths 84 and 86 are so formed that transfer is made between accelerator 68 and the cam paths at the vertical position of beam 72 without loss of contact between the accelerator and the cam paths. The lengths of rammer arm 80 and extractor arm 82 have a predetermined re-

lationship to the longer length of beam 72 for a mechanical advantage to assist cam paths 84 and 86 in actuating carrier 40 for full travel thereof between the forward and rearward positions.

After cartridge 20 is transferred into chamber 26 by rammer 42, the base of the cartridge is supported for discharge by a breech member 96 which is slidably disposed in barrel extension 28 for substantially lateral movement adjacent the breech of barrel 24 between a breech open and a breech closed position. Breech member 96 includes an anvil 98 which, when the breech member is in the breech open position, is clear of chamber 26 so that fired case 64 may be removed therefrom or cartridge 20 transferred thereinto. When breech member 96 is actuated to the breech closed position, anvil 98 is inserted between extractor 50 and rammer 42 in clearance 56 to support the base of the chambered cartridge 20 for discharge.

A roller 100 depends from the base of breech member 96 for sliding engagement with a cam groove 102 provided in a shelf 103, extending rearwardly from the front end of receiver 14, for converting longitudinal displacement of barrel extension 28 to lateral movement of the breech member. Cam groove 102 includes an arcuate portion 104 which is disposed so as to actuate breech member 96 to the breech closed position during the final half of the counterrecoil movement of barrel extension 28 and to the breech open position during the first half of the recoil stroke thereof. A linear portion 106 extends rearwardly from arcuate portion 104 and slidably receives roller 100 during the rearward half of the reciprocal travel of barrel extension 28 to secure breech member 96 in the breech open position during the ramming and extracting operations of carrier 40. A dwell portion 108 extends forwardly from the opposite end of arcuate portion 104 to receive roller 100 when barrel 24 is in full forward position to lock breech member 96 in the breech closed position. The length of dwell portion 108 is predetermined so that, when roller 100 enters arcuate portion 104 therefrom to actuate breech member 96 to the breech open position, sufficient time has elapsed for a reduction in the gas pressure in barrel 24 to where it is safe to uncover fired case 64 but with enough gas pressure remaining in the barrel to assist in the extraction of the fired case from chamber 26.

Cartridge 20, after being transferred to chamber 26, is discharged by a hammer 110 which is journaled on a shaft 112 mounted through the left one of the side plates 36. Hammer 110 is disposed in channel 32 adjacent cam plate 88 and, therefore, clear of a pathway through channel 32 for passage of fired case 64 to ejection port 34. Hammer 110 is provided with a striker portion 116 and an extension 118 disposed on the opposite side of shaft 112 from such striker portion. A wheel 120 is mounted to extension 118 by means of an axle 119 which extends therefrom so that the wheel is disposed for engagement with an arcuate engagement surface 122 recessed in the top front corner of cam plate 92. Engagement surface 122 is engaged by wheel 120 during the initial recoil movement of barrel 24 for pivoting hammer 110 to the cock position while breech member 96 is being actuated to the breech open position so as not to interfere with the subsequent movement of carrier 40 to the rearward position. Hammer 110 is held in the cock position until barrel extension 28 is adjacent forward battery position and breech member 96 is locked in breech closed position by the rolling contact of wheel 120 with a top side 124 of cam plate 92 leading from engagement surface 122. When wheel 120 is adjacent engaging surface 122 during counterrecoil movement of barrel extension 28, hammer 110 is retained in the cock position by the releasable engagement thereof by a sear 126 which is mounted to the left one of the side plates 36. Hammer 110 is biased to the firing position by a spring-biased plunger 128 which is dis-

posed in barrel extension 28 so as to press against extension 118.

Connection between striker portion 116 and primer 132 of a cartridge 20 in chamber 26 is made by a firing pin 134, which is disposed through anvil 98 for sliding longitudinal movement against such primer when breech member 96 is in the breech closed position, and a firing pin extension 136 which is angularly disposed through carrier 40 so that the rear end of the firing pin extension is contactable by the striker portion and the front end is contactable with firing pin 134 when the carrier is in the forward position and breech member 96 is in the breech closed position. Firing pin extension 136 is slidingly disposed in carrier 40 so that the energy of hammer 110 may be transferred to firing pin 134.

Fired case 64 is ejected from receiver 14 by an ejector 138 which depends from the underside of feed tray 18 so as to contact the upper portion of rim 47 when the fired case, gripped between extractor 50 and rammer 42, clears breech member 96. Through the contact of ejector 138 with rim 47, fired case 64 is pivoted around hook 58 and expelled downwardly through channel 26 and out ejection port 34. As stated hereinbefore, there is very little overtravel required of carrier 40 for the ramming operation thereof and, therefore, in order to have as early an ejection of fired case 64 as possible so as not to interfere with the ramming function, a vertically disposed notch 140 is provided through the rear portion of breech member 96 to provide a clearance for the downward passage of the neck of the fired case to advance the point at which ejector 138 may contact the fired case. Firearm 12 is held inoperative by means of a trigger 142 which releasably holds barrel extension 28 in the recoil position.

When firearm 12 is in battery, barrel extension 28, under the pressure of the springs 38, is biased to the forward position along with barrel 24. Carrier 40, consequently, is in the forward position thereof in barrel extension 28 with rammer 42 and extractor 50 jointly contacting rim 47 of a cartridge 20 which is housed within chamber 26 and is supported for discharge therein by breech member 96 which is disposed in the breech closed position with anvil 98 inserted between the rammer and extractor. Hammer 110 is releasably held in cock position by sear 126, and firing pin extension 136 is in registry with firing pin 134 which is in alignment with primer 132 of the chambered cartridge 20.

The release of hammer 110 is automatically controlled by sear 126 through a conventional release mechanism noted at 127 in Fig. 5. When hammer 110 is released by sear 126, the energy imparted thereto by spring-biased plunger 128 is transmitted through firing pin extension 136 to firing pin 134 for ignition of primer 132 of chambered cartridge 20. Upon discharge of chambered cartridge 20, barrel 24 with barrel extension 28 connected thereto is energized for recoil movement in receiver 14, whereupon roller 100 on breech member 96 moves along dwell portion 108 of cam groove 102 to prevent movement of the breech member until the gas pressure in the barrel is reduced sufficiently for the fired case 64 to be unblocked yet with sufficient pressure remaining in the barrel so that, when the roller enters arcuate portion 104 to move the breech member to the breech open position, the extraction of the fired case is assisted by the residual gas pressure. Also, during the initial portion of the recoil movement of barrel extension 28, hammer 110 is pivoted to the cock position by the engagement of wheel 120 with engaging surface 122 and is retained in the cock position during the remainder of the recoil movement of the barrel extension.

Breech member 96 is fully actuated to the breech open position, during the first half of the recoil travel of barrel extension 28, and then, at the midpoint of the recoil travel, follower 94 on extractor arm 82 becomes engaged by cam path 86 whereupon accelerator 68 is pivoted to

move carrier 40 rearwardly and the mass of barrel 24 and barrel extension 28 is connected to carrier 40 through such engagement together with the engagement of roller 76 on the end of beam 72 with groove 78 in the carrier.

- 5 With the rearward movement of carrier 40, fired case 64 is removed from chamber 26 through the engagement of hook 58 with extractor groove 62 in the fired case, and the fired case is maintained longitudinally disposed during the extraction stroke through the joint engagement of rim 10 47 by extractor 50 and rammer 42. When beam 72 is vertically disposed, extractor arm 82 becomes disengaged from cam path 86 and rammer arm 80 engages cam path 84 to complete the actuation of carrier 40 to the rearward position thereof. As carrier 40 nears the end of the rearward position thereof, the base of fired case 64 contacts ejector 138 for disengagement from the extractor and ejection through channel 32 in barrel extension 28 and out ejection port 34.

At the end of the recoil stroke of barrel 24, the springs 20 38, which were compressed during the recoil stroke thereof, energize barrel 24 for the subsequent counter-recoil stroke. During the initial half of the counterrecoil stroke of barrel extension 28, follower 90 on rammer arm 80, which is engaged by cam path 84, pivots accelerator 25 68 forwardly until beam 72 reaches its vertical position when follower 90 leaves cam path 84 and follower 94 enters cam path 86 to complete the movement of carrier 40 to the forward position. During forward movement of carrier 40, front end 44 of rammer 42 contacts the 30 cartridge 20 indexed in throat 22 to transfer the cartridge into chamber 26 of barrel 24. When the rammed cartridge 20 becomes longitudinally disposed in chamber 26, front end 44 slides over rim 47 for contact of underside 48 therewith and, during continued forward movement of carrier 40, hook 58 rides over rim 47 for engagement with extractor groove 62.

During the final half of the counterrecoil stroke of barrel extension 28, roller 100 enters arcuate portion 104 of cam groove 102 to actuate breech member 96 from the 40 breech open to the breech closed position with anvil 98 being laterally inserted between rammer 42 and extractor 50 to support the base of cartridge 20 in chamber 26 for discharge and aligns firing pin 134 between primer 132 of the chambered cartridge and firing pin extension 136. 45 Also, during the final movement of barrel extension 28 to the forward battery position, wheel 120 of hammer 110 moves adjacent engagement surface 122 to release the hammer into engagement by sear 126, and roller 100 enters dwell portion 108 to lock breech member 96 in the breech closed position.

55 From the foregoing it is clearly apparent that there is provided herein a loading, firing and unloading mechanism of compact design so as to be housed within a receiver having a short length for mounting within a small space, as in a tank, with the mechanism being simple in design, rugged in construction and positive in operation.

Although a particular embodiment of the invention has been described in detail herein, it is evident that many variations may be devised within the spirit and scope 60 thereof and the following claims are intended to include such variations.

I claim:

1. In a firearm having a receiver, a barrel mounted in the receiver and provided with a chamber for the discharge of a cartridge having an annular rim adjacent the base thereof and a breech member slidably disposed in the receiver adjacent the barrel chamber for lateral reciprocation between a breech open and a breech closed position responsive to forces produced by the discharge 65 of the cartridge in the barrel chamber, a loading and unloading mechanism including a carrier slidably disposed in the receiver for longitudinal reciprocation between a rearward position and a forward position adjacent the breech of the barrel, a rammer extending integrally forward from said carrier, an extractor pivotally disposed

on said carrier for forward extension therefrom to co-engage with said rammer the rim of the cartridge when in the barrel chamber for removing the fired case of the cartridge therefrom during movement of said carrier to the rearward position thereof and for maintaining the fired case longitudinally disposed during the recoil travel of said carrier, and a clearance formed between said extractor and rammer for passage of the breech member to the breech closed position when said carrier is in the forward position thereof and said rammer and extractor are in co-engagement with the rim of the chambered cartridge.

2. In a firearm having a receiver, a barrel mounted in the receiver and provided with a chamber for the discharge of a cartridge provided with an extractor groove and a rim formed thereby and a breech member disposed in the receiver adjacent the barrel chamber for lateral reciprocation between a breech open and a breech closed position responsive to forces produced by the discharge of the cartridge in the barrel chamber, a loading and unloading mechanism inclosed in the receiver and including a carrier disposed for longitudinal reciprocation between a rearward position and a forward position adjacent the barrel chamber, a rammer extending integrally forward from said carrier, an extractor pivotally mounted on said carrier so as to extend forwardly therefrom, a clearance formed between said rammer and extractor for passage of the breech member to the breech closed position when said carrier is in the forward position, a hook disposed on the forward end of said extractor for engagement with the extractor groove of the chambered cartridge, spring means disposed between said extractor and said carrier for biasing said hook into the extractor groove, and a side of said rammer facing said extractor, said side being disposed for frictional contact with the rim of the chambered cartridge to oppose the displacement of the fired case of the cartridge by said extractor, whereby said hook is maintained in engagement with the extractor groove and the fired case is longitudinally disposed when removed from the barrel chamber by said extractor during movement of said carrier to the rearward position thereof.

3. In a firearm having a receiver with a barrel slidably disposed therein for reciprocation responsive to forces produced by the discharge of a cartridge in a chamber thereof, the cartridge being provided with a rim adjacent the base thereof and a centrally located primer, a barrel extension connected to the barrel for reciprocation therewith and provided with a channel vertically disposed therein to provide communication between the barrel chamber and an ejection port in the underside of the receiver, a breech member slidably disposed in the barrel extension for lateral reciprocation therein adjacent the barrel chamber, cooperating cam means disposed in the receiver and on the breech member for actuating the breech member between a breech open and a breech closed position responsive to longitudinal reciprocation of the barrel extension, and a firing pin extending longitudinally through the breech member for movement against the primer of the chambered cartridge for discharge thereof, a mechanism including a carrier slidably disposed in the barrel extension for longitudinal reciprocation in the channel between a rearward position and a forward position adjacent the barrel chamber, a rammer extending integrally forward from said carrier, an extractor pivotally disposed on said carrier for forward extension therefrom to co-engage with said rammer the rim of the cartridge when in the barrel chamber, a clearance formed between said extractor and rammer for passage of the breech member to the breech closed position when said carrier is in the forward position thereof and said rammer and extractor are in co-engagement with the rim of the chambered cartridge, a spring-energized hammer pivotally disposed in the barrel extension channel away from the longitudinal axis of the barrel

to provide space in the channel for the ejection of the fired case of the cartridge therethrough after discharge, and a firing pin extension slidably mounted in said carrier and disposed angularly therethrough for transferring the energy in said hammer to the firing pin when the breech member is in the breech closed position and said carrier is in the forward position thereof.

4. In a firearm having a receiver with a barrel slidably disposed therein for longitudinal reciprocation in a recoil and a counterrecoil stroke responsive to the forces produced by the discharge of a cartridge in a chamber of the barrel, the cartridge having a rim formed by an annular extractor groove, a barrel extension connected to the breech of the barrel for reciprocation therewith in the receiver and provided with a vertically disposed channel to provide communication between the barrel chamber and an ejection port in the bottom of the receiver, a breech member slidably disposed in the barrel extension for lateral reciprocation adjacent the breech of the barrel between a breech open and a breech closed position, and a feeding mechanism mounted on the top side of the receiver for successively indexing the cartridges in a throat leading into the receiver, a loading and unloading mechanism inclosed in the receiver rearwardly of the breech of the barrel and including a carrier slidably disposed in the barrel extension for longitudinal reciprocation in the channel thereof between a rearward position and a forward position adjacent the breech of the barrel, a rammer extending integrally forward from the top of said carrier and disposed to transfer the cartridges from the throat into the barrel chamber during movement of said carrier to the forward position thereof by means of a front end having contact with the base of the cartridge until the cartridge is longitudinally positioned in the barrel chamber, an extractor pivotally mounted on the underside of said carrier so as to extend forwardly therefrom, a clearance formed between said rammer and extractor for passage of the breech member to the breech closed position when said carrier is in the forward position, a hook disposed on the forward end of said extractor for engagement with the extractor groove of the chambered cartridge when said carrier is in the forward position thereof, spring means disposed between said extractor and said carrier for biasing said hook into the extractor groove to remove the fired case of the cartridge from the barrel chamber during movement of said carrier to the rearward position thereof, and an underside of said rammer disposed for frictional contact with the rim of the cartridge when longitudinally disposed in the barrel chamber to oppose the displacement of the fired case by said spring means for maintaining said hook in engagement with the extractor groove and the fired case longitudinally disposed during extraction from the barrel chamber.

5. The loading and unloading mechanism as defined in claim 4 and including an accelerator provided with a hub portion journaled to the barrel extension on a pin extending laterally through the barrel extension adjacent the bottom thereof and equidistantly between the locations of the rear-end of said carrier when in the forward and rearward positions thereof, a beam extending integrally upward from said hub for displacement between a rearward and a forward position spaced equidistantly from a vertical position, a rammer arm extending integrally upward and rearward from said hub portion and an extractor arm extending upwardly and forwardly from said hub portion when said beam is in the vertical position, and cam means for actuating said carrier between the forward and rearward positions thereof, said cam means including a roller mounted to the free end of said beam for sliding engagement with a vertical groove in the adjacent side of said carrier and adjacent the rear end thereof for converting pivotal movement of said accelerator to translational movement

of said carrier without free movement therebetween, a first cam path disposed in the receiver for cooperation with a follower rotatably mounted to the free end of said rammer arm for pivoting said beam between the rearward and vertical positions thereof responsive to reciprocation of the barrel extension, and a second cam path disposed in the receiver for cooperation with a follower rotatably mounted to the free end of said extractor arm to controllably pivot said beam between the forward and vertical positions thereof responsive to reciprocation of the barrel extension, said first and second cam paths being arranged so as to pivot said beam between the forward and rearward positions thereof during the rearward half of the reciprocal movement of the barrel extension and for one of said first and second cam paths to be engaged by said accelerator during actuation of said carrier between the forward and rearward positions thereof to connect the mass of the barrel and barrel extension to said carrier during reciprocation thereof.

6. The loading and unloading mechanism as defined in claim 4 and including an accelerator disposed within the channel in the barrel extension, said accelerator including a hub journaled to the barrel extension to mount the accelerator for pivotal displacement and a beam extending from said hub, cooperating cam means on said beam and said carrier for converting pivotal displacement of said accelerator to longitudinal translation of said carrier and connecting the barrel and barrel extension to said carrier for relative longitudinal movement, and cam means interposed between said accelerator and

the receiver for converting the translation of the barrel to pivotal displacement of said accelerator and transferring the energy in the barrel and barrel extension through said accelerator to said carrier.

- 5 7. The loading and unloading mechanism as defined in claim 4 and including an accelerator mounted on the barrel extension for pivotal displacement through an arc of a predetermined angularity which is of the order of 75°, cam means on said accelerator and said carrier for 10 converting pivotal displacement of said accelerator to longitudinal translational displacement of said carrier, a first cam means fixed to the receiver and disposed for sliding engagement by said accelerator for converting longitudinal displacement of the barrel and barrel extension to pivotal displacement of said accelerator through one-half of the arc, and a second cam means fixed to the receiver and disposed for sliding engagement by said accelerator for converting continued longitudinal displacement of the barrel and barrel extension in the same direction to pivotal displacement of said accelerator through the remaining half of the arc.
